UNITED STATES PATENT OFFICE.

AUGUST W. MELANDER, OF SAN FRANCISCO, CALIFORNIA, ASSIGNOR, BY DIRECT AND MESNE ASSIGNMENTS, TO FOUNTAIN FAUCET COMPANY, A CORPORATION OF MINNESOTA.

VALVE.

1,276,673.

Specification of Letters Patent. Patented Aug. 20, 1918.

Application filed December 7, 1915. Serial No. 65,502.

To all whom it may concern:

Be it known that I, AUGUST W. MELANDER, a subject of the King of Sweden, and residing at the city and county of San Francisco and State of California, have invented new and useful Improvements in Valves, of which the following is a specification.

This invention relates to a faucet valve.

The object of the present invention is to provide a simple, substantial self-closing valve particularly intended for use in connection with a fountain faucet, forming the subject matter of a co-pending application, entitled "fountain faucet," filed December 7, 15 1915, Serial No. 65,501.

Further objects will hereinafter appear.

The invention consists of the parts and the construction and combination of parts, as hereinafter more fully described and 20 claimed, having reference to the accompanying drawings, in which—

Figure 1 is a side elevation of a faucet, showing the application of the invention.

Fig. 2 is a cross section on line 2—2, 25 Fig. 1.

Fig. 3 is a cross section on line 3—3, Fig. 2.

Fig. 4 is a plan section on line 4—4, Fig. 1.

Fig. 5 is a view similar to Fig. 3, showing the distributing valve turned into a position where water is permitted to discharge through the upper passage.

Fig. 6 is a perspective view of the distributing valve.

Fig. 7 is a perspective view of one end of the main valve stem.

Referring to the drawings in detail, A indicates a faucet casing, provided with an 40 intake 2, which is adapted to be connected with a water main or any other suitable source of supply, and 3 and 4 indicate a pair of discharge passages, the upper of which terminates in a drinking fountain 5, while 45 the lower terminates in an ordinary faucet bib 6. Formed in the casing intermediate of the intake and discharge passages is a valve chamber 7, one end of which communicates through an opening 8 and a passage 9 with 50 the intake 2, while the other end is closed by a suitable form of stuffing box 10. Extending through the stuffing box is a valve stem 11 on the inner end of which is secured a disk 12, the purpose of which will later be 55 described. The valve stem proper, indicated

at 11 is adapted to be turned by a handle 13 and is also adapted to be reciprocated within the valve chamber and through the stuffing box 10 by the cam faces 14 and 15. The cam 14 is stationary and is formed as an integral part of the stuffing box cap 10^a, while the cam 15 is carried or formed integral, with the handle 13. Turning movement of the handle will, therefore, be transmitted to both turn stem 11 and simultaneously move 60 it outwardly through the stuffing box and chamber 7. The cam face 15 is double and the valve handle 13 may, therefore, be turned in either direction to assume either dotted line position shown at 13^a and 13^b. 70 It is, however, normally held in the full line position, shown in Fig. 1 by means of a spring 16 interposed between the disk 12 and the end of the stuffing box 10. This spring exerting its pressure against the disk 75 normally forces the stem inwardly and this together with the arrangement of the cams 14 and 15 forms a means whereby the valve mechanism hereinafter to be described is not only normally, but also automatically 80 closed.

Referring to Fig. 2, it will be seen that a valve seat 8^a is formed on one side of the opening 8 and that a valve 17 is loosely mounted in the end of the stem 11 in a position where it is adapted to form a closure for the opening 8 to prevent admission of water through passages 2, 9 and opening 8.

The valve 17 is preferably independent of the main stem to this extent, that it is provided with a stem 18, which is loosely supported in the recess 19 formed in the end of the stem 11. The valve chamber 7 is circular in cross section, as shown in Figs. 3 and 5 and mounted interior of said chamber 95 is a split sleeve valve 20. This valve is provided with a single discharge opening 21, which is adapted to register with either one of the other of the discharge openings 3 and 4; means must, therefore, be provided for 100 turning the sleeve valve and this is accomplished by forming a lug 22 on the disk 12 which projects out sufficiently far to fill the space between the valve casing and the split 20^a formed in the sleeve valve. Turning 105 movement of the stem 11 by means of handle 13 is thus imparted through disk 12 and lug 22 to turn the sleeve valve 20 in one direction or another. When turned to assume the dotted line position, shown at 13^a regis- 110

ter will be made between discharge opening 21 and the discharge passage 23, while turning movement of the handle to the position shown at 13^b brings opening 21 into alignment with the lower discharge passage 4. The turning movement of the stem to assume either of the positions described simultaneously pulls the stem with valve 17 away from the seat 8^a, permitting water to enter from passages 2 and 9 directly into the valve chamber 7, from where it is permitted to escape into one or the other of the discharge passages 3 and 4.

When it is desired to close off the water supply it is only necessary to release the handle; the spring 16 will then force the stem 11 with connected valve 17 back against the seat 8^a and, therefore, cut off the main source of water supply, and will at the same time turn the sleeve back to the normal closed position, shown in Fig. 3, where the discharge passage 21 assumes the position intermediate of passages 3 and 4. No water will then be discharged through either passage and all tendency to leakage is prevented, as no water is permitted to enter the valve chamber 7. The stuffing box 10 and sleeve valve 20 are in this manner relieved of the main water pressure and leakage through these parts should, therefore, be entirely eliminated.

The stuffing box is in this instance provided with means for automatically tightening the packing as it may wear. This is accomplished by placing a loose follower 10^b between the packing and the spring 16. A loose washer 28 is also preferably interposed between the opposite end of the spring and the disk 12 and this together with the follower 10^b eliminates any turning tendency of the spring when the stem is turned by the handle 13, thus preventing the tearing of the packing or unnecessary twisting of the spring, which might interfere with the operation of the mechanism, as a whole.

The valve as a whole is simple, substantial in construction, is easily opened to direct the water either to the fountain 5 or the faucet 6, and is furthermore automatically closed when the handle 13 is released. It is, therefore, impossible to go off and leave the faucet running.

Copies of this patent may be obtained for five cents each, by addressing the "Commissioner of Patents, Washington, D. C."

The provisions of the valve 17 is one of the important features of the present invention, as this when closed takes all the pressure of the water supply, thereby relieving the main operating parts, such as the sleeve or distributing valve 20 and the stuffing box 10 from unnecessary wear and strain.

The materials and finish of the several parts of the device are otherwise such as the judgment and experience of the manufacturer may dictate.

I wish it understood that various changes in form, proportions and minor details of construction may be resorted to within the scope of the appended claim and that I do not wish to limit myself to the specific design and construction here shown.

Having thus described my invention, what I claim and desire to secure by Letters Patent is—

A faucet, comprising, in combination, a faucet casing having an upturned discharge passage and a down turned discharge passage, a cylindrical distributing chamber connected by its side through separate ports with said discharge passages, an intake passage connected with one end of said distributing chamber, a valve stem entering the other end of said chamber, a stuffing box in said chamber through which said stem extends and formed with a cam face, a cam on said stem coöperating with said cam face to reciprocate said stem by the revolution of said stem, a valve removably mounted on the inner end of said stem adapted to close the passage entering said distributing chamber in one position of said stem, a spring urging said valve into closing position, an expansible split sleeve valve rotatable in said distributing chamber and having a port adapted to register with either one of said discharge passages and in intermediate position closing both of said passages, and a connection between said stem and sleeve valve for rotating the latter by said stem.

In testimony whereof I have hereunto set my hand in the presence of two subscribing witnesses.

AUGUST W. MELANDER.
